TRAY FOR URINALYSIS EQUIPMENT

Edward J. Hill, 1660 Lochridge, Bloomfield Hills, Mich.

Filed May 7, 1964, Ser. No. 79,871

Term of patent 14 years

(Cl. D83—1)

FIG. 1 is a top plan view for a tray for urinalysis equipment embodying my new design; and

FIG. 2 is a bottom view; and

FIG. 3 is a side elevational view; and

FIG. 4 is a longitudinal sectional view taken on the line 4—4 of FIG. 1; and

FIG. 5 is an end elevational view; and

FIG. 6 is a cross sectional view taken on the line 6—6 of FIG. 1.

I claim:

The ornamental design of a tray for urinalysis equipment, substantially as shown.
